UNITED STATES PATENT OFFICE

HAROLD RUSCHER, OF NEW YORK, N. Y.

TICKET DISPENSING

Application filed March 7, 1929. Serial No. 344,945.

This invention relates to cabinets, particularly to cabinets used for dispensing railway tickets and more especially railway tickets made in the form of long narrow strips, commonly known as interline railway tickets.

At present, the type of tickets which it is contemplated will be dispensed by this invention are commonly dispensed from a large vertical cabinet placed back of the ticket agent. The tickets are generally hung on pegs or hooks arranged horizontally in rows and vertically in a series in such manner that only the upper or identifying indicia end of a ticket is exposed. Where a very large number of interline tickets must be kept on hand these cabinets assume rather formidable proportions. The uppermost row of the series is often a very considerable distance above the level of the eye of the person standing on the floor upon which the cabinet rests and the lowermost row of the series is quite often as low as the knee of such a person. These cabinets are generally provided either with swinging doors or a sliding door because it is necessary at times to secure tickets against pilfering. During business hours, however, the case is generally open and the tickets are fully exposed to view.

These prior cabinets are open to quite a few objections. In order to select a ticket the ticket agent must turn his back upon the customer. The indicia on those rows of the series somewhat above the level of the eye are difficult to read and those below the level of the eye are also difficult to read because the ticket agent is obliged to stoop over in order to bring his eye to the proper position to read the indicia thereon. As the doors or sliding cover are generally left entirely open during business hours there is a large accumulation of floating dust and dirt continually settling upon the tickets, so that in time they become quite covered and objectionable to handle. The door or cover of these cabinets being constantly open offers an opportunity for pilfering.

A principal object of applicant's invention is to provide a cabinet for dispensing tickets of the type specified which will ob-

viate most of the objections which may be raised against the present type of cabinets.

Applicant by this invention contemplates a cabinet for dispensing tickets of the type specified which will be so constructed and positioned that the ticket agent will always face the customer while dispensing tickets, and which will be relatively compact, will in use always expose the indicia end of the tickets at substantially the same distance from the eye of the ticket agent, will keep all of the tickets concealed from view and protect them from flying dust and dirt except at the moment a particular ticket is being dispensed; and will secure the tickets against pilfering.

This invention contemplates arranging tickets of the type specified in rows upon a bar and further contemplates arranging a series of such bars closely adjacent one another around the periphery of an arc of a circle and further contemplates positioning the series of bars at each end upon a sector of a circle pivoted at the center of the circle.

Further objects and advantages will appear as the description of a particular physical embodiment selected to illustrate the invention progresses and the novel features of the invention will be particularly pointed out in the appended claims.

In describing the invention in detail and the particular physical embodiment selected to illustrate the invention reference will be had to the accompanying drawings and the several views thereof in which like characters of reference designate corresponding parts throughout the several views, and in which:

Figure 1 is a front face view of a device embodying applicant's invention; Fig. 2, is a cross-sectional view of the device, as shown by Fig. 1, on the plane indicated by the line II—II; Fig. 3, is a cross-sectional view of the device as shown by Fig. 2, on the plane indicated by the line III—III, viewed in the direction of the arrows at the ends of the line; Fig. 4, is a detail view of a bar with hook attached used with applicant's invention; Fig. 5, is a detailed top plan view of a counter balance used with applicant's invention.

The physical embodiment of applicant's invention shown in the drawings has been arranged as a sort of case or cabinet providing a counter top. The counter top is designated 1 and is well shown in Figs. 1 and 2. The counter or top is supported by the front closure 2, as shown in Fig. 2, and the side closures 3 and 4, as shown in Fig. 1. The front closure 2 and the side closures 3 and 4 are made of such height that the counter 1 is positioned about the proper height to be convenient for a customer standing in front of the case and also convenient for a ticket agent standing at the back of the case.

At the back of the case there is a bar 5 extending between the side closures 3 and 4. Pivoted to this bar 5 in any suitable or appropriate manner as by hinges 6 and 7 is a back closure 8. This back closure 8 is made to tightly close the back of the case or cabinet, that is, the opening between the bar 5 and a bar 9. The remainder of the area of the back face being closed, if desired, by a drawer front as 10 and a small lower hinged door as 11.

The pivoting door 8, at both the right and the left hand sides as viewed in Fig. 1, has sectors attached thereto, as 12 and 13, as best shown in Fig. 3. The sector 12 is also well shown in Fig. 2. These sectors may be any desired portion of a circle within the limits of the capacity of the particular cabinet upon which they are mounted. In the particular embodiment selected to illustrate this invention, as shown by Fig. 2, the sector is a little greater than a quadrant.

Extending from one sector 12 to the other sector 13 at the lower inside corner as best shown in Fig. 2 is a bar 14 which serves to make the outer ends rigid and maintains a proper spacing one from the other.

Upon each of the opposing faces of the sectors is a toothed or shouldered arcuate member 15. This member 15 is secured to the face of a sector in any appropriate manner and in such a manner that the top of the teeth or outside of the shoulders will lie a short distance within the outer periphery of the sector, all as best shown in Fig. 2.

Extending between the sectors in a series are the ticket bars 16, shown in Fig. 2 and in detail in Fig. 4. These ticket bars are preferably formed of metal and rest upon the shoulders 17 of the arcuate toothed member 15 and at each end are attached to an arcuate toothed member by any suitable or appropriate means, as by screws 18, as best shown in Fig. 3. These ticket bars or cross bars are formed with a bend 19 intermediate their edges as best shown in Fig. 4 and are provided with a peg or hook 20 as best shown in Fig. 4.

The tickets as 21 which are to be dispensed are provided with an orifice adjacent their upper or indicia end and are hung upon ticket

bars 16 by means of the peg or hook 20 with their free end hanging loosely as shown in Fig. 2.

When a ticket agent desires to dispense one of the tickets he grasps the handle 22 pulling outwardly, thereby causing the back closure 8 to pivot upon the hinges as 6 and 7 carrying with it the sectors 12 and 13 and the series of the ticket bars 16 and all of the tickets hung on said bars. The upper end 75 of each ticket bears an indicia thereon as: New York to Los Angeles, or New York to San Diego, as shown in Fig. 3. These particular indicia bearing ends come successively within easy reading distance of the eye of the agent as the back closure 8 is swinging outwardly until when it has reached the extreme position as shown by the dotted line 2 each has come successively before the eyes of the agent. When the proper indicia presents itself one ticket bearing that indicia may be removed from the bunch of tickets and from the hook by a simple manual movement. The ticket having been removed, the back closure 8 is returned to place, as shown in Fig. 90 2 in full line, and the tickets are once again protected and concealed from view.

It is desirable that the exertion required of a ticket agent in pivoting the back closure 8 be reduced to a minimum. In order to provide for this applicant has supplied a counter balancing device. This device is attached to the back of the front wall of the cabinet by screws, as 23, as best shown in Fig. 2. This device as shown in Fig. 5 includes supports 100 24 and 25 in which is journaled the shaft 26. This shaft 26 has a drum 27 revolvably mounted thereon. Within the drum 27 is a spiral spring 28 as shown in Fig. 2. One end 29 of which is attached to shaft 26 and the other end 30 of which is attached to drum 27. Wound about the drum 27 is a cord 31 one end of which is attached to a sector as at 32 and the other end of which is attached to the drum 27. After the cord 31 has been 110 attached as shown in Fig. 2 the crank arm 34 is rotated so as to tension the spiral spring 28. The tension should be such that when all of the parts are as shown in full line in Fig. 2 there will not be a sufficient pull on the cord 31 to raise the member 14 together with the sectors. When this tension has been obtained the pawl 35 is dropped into the path of a tooth 36 of the ratchet wheel 37 attached to 115 36 so that the position of the spring is maintained. When an agent grasps the handle 22 to pivot the closure 8 outwardly he is assisted by the tension on the cord 31 during the preliminary movement but during the final operation of the movement if the member 8 is oscillated outwardly as far as it will go tension will be exerted on the cord 31 to somewhat restrain further outward movement. By such device the manual force necessary to oscillate the member 8 is lessened 120

125

130

because at the point of the movement where the greatest force must be used to cause the oscillation assistance is given by the counter balancing device, that is, when the device is in the position as shown by full lines in Fig. 5 and also when the device is in the position as shown by dotted lines in Fig. 2.

If an agent desires to leave the ticket cabinet unattended and desires to prevent pilfering he merely has to lock the closure 8 as by means of the lock 28 and perhaps in some cases lock the closure 11 as by the lock 39 although such closure is generally kept locked in practice.

15 Although I have described one particular physical embodiment of my invention and explained the principle thereof, nevertheless, I desire to have it understood that the particular physical embodiment shown in the 20 drawings and explained in the specification is merely illustrative but does not exhaust the possible physical embodiments of the idea of means underlying my invention.

What I claim as new and desire to secure 25 by Letters Patent of the United States, is:

1. In a ticket dispensing cabinet, in combination: a pivoted closure; a series of ticket bars, each bar being provided with a plurality of ticket supporting hooks; an arcuate 30 support for the bars and means for attaching said arcuate supports to the closure.

2. In a ticket dispensing device, in combination: a plurality of ticket supporting bars each provided with a plurality of ticket 35 supporting members and arranged substantially in the arc of a circle; means to support said ticket bars, said means being oscillatable on a pivot at substantially the center of a circle of which the arc upon which the hooks 40 are arranged is a part.

3. In a ticket dispensing device; in combination; ticket supports, arranged in a row horizontally and substantially in the arc of a circle vertically; means adapted to oscillate 45 in a vertical plane carrying said supports.

4. In a ticket dispensing device, in combination: ticket supports, arranged in a row horizontally and substantially in the arc of a circle vertically; means adapted to oscillate 50 in a vertical plane, carrying said supports and means acting to counter balance the weight of the said last named means, when the last named means is in either one of its extreme positions.

5. In a ticket dispensing device, in combination: ticket bars each provided with a plurality of ticket hooks; arcuate shouldered member at each end of each bar; two sectors, one attached to each arcuate member; a pivoted member and means to support the sectors on the pivoted member whereby the bars and the sectors may pivot in a vertical plane.

6. In a ticket dispensing device, in combination: ticket bars, each provided with a plurality of ticket hooks, said ticket bars

each lying in a horizontal plane but the series being arranged in a vertical plane in substantially the arc of a circle; means to support said bars and to allow oscillation as a whole in a vertical plane.

7. In a ticket dispensing device, in combination: ticket bars each provided with a plurality of ticket hooks, said ticket bars each lying in a horizontal plane but the series being arranged in a vertical plane in substantially the arc of a circle; means to support said bars and to allow oscillation as a whole in a vertical plane and means to assist the initial movement from either of the extreme oscillated positions.

HAROLD RUSCHER.
